METHOD OF PREPARING INNER TRIM PANELS

Andrew J. Jarosik, Detroit, Mich., assignor to The Murray Corporation of America, Detroit, Mich., a corporation of Delaware

Application September 28, 1936, Serial No. 102,971

1 Claim. (Cl. 154—2)

This invention relates to inner trim panels. More particularly it relates to a novel and improved method of manufacturing inner trim panels which serves to provide a construction having ornamental embossed surface decorations.

It is a primary object of the present invention to provide a method for manufacturing inner trim panels which method may be simply, conveniently and cheaply practiced and which at the same time results in the production of an inner trim panel having a particularly attractive surface ornamentation.

It has long been conventional to manufacture inner trim panels including a relatively stiff cardboard backing sheet, a layer of non-woven fibrous padding material, and to cover the same with a layer of fabric finish material which is tightly stretched over the padded surface of the backing sheet. The present invention contemplates the provision of a method which serves to provide ornamentation upon the finished surface of the trim panel in order to break up the surface thereof and provide attractive beaded or other effects which serve to render the trim panel as a whole more attractive in appearance.

Many other and further objects, advantages and features of the present invention will become more clearly apparent from the following specification when considered in connection with the accompanying drawing forming a part thereof.

In the drawing:

Fig. 1 is a perspective view of an inner trim panel for a vehicle door, constructed in accordance with the method of the present invention.

Fig. 2 is a fragmentary sectional view through a die press utilized in the practice of the present method.

Fig. 3 is a fragmentary sectional view taken substantially on the line 3—3 of Fig. 1 illustrating the manner in which the padded backing sheet is embossed prior to the application of the fabric finish material.

Fig. 4 is a fragmentary sectional view similar to Fig. 3 showing the construction of a completed trim panel manufactured in accordance with the present method.

Fig. 5 is a fragmentary sectional view similar to Figs. 3 and 4 illustrating the edge portion of a trim panel manufactured in accordance with a modified method of the present invention.

Fig. 6 is a fragmentary sectional view similar to Fig. 5 illustrating a portion of a trim panel manufactured in accordance with a still further modified form of the invention.

With more particular reference to the draw-

ing, the trim panel construction disclosed in Figure 1 illustrates a trim panel primarily adapted for covering the lower surface of the left hand front door of a vehicle body. As is conventional in construction of this general character the trim panel is formed with the outer configuration substantially congruent to the surface to which it is to be applied and is provided with a hole 8 therethrough to permit the passage of the window regulator mechanism and a second hole 9 adapted to accommodate the latch mechanism of the door. The trim panel includes a backing sheet 10 which may be formed of cardboard or other suitable similar material and which is blanked out to an exterior configuration substantially the same as the shape desired in the completed trim panel. A section of non-woven fibrous material 11, composed of loosely felted jute fibre is blanked out to a form substantially coextensive with the backing sheet 10.

The backing sheet 10 is sprayed with liquid adhesive which serves to secure the padding material thereto and is covered in predetermined portions with a relatively heavy coating of thick liquid adhesive 12. This extra coating of liquid adhesive is applied to the panels throughout the areas thereon in which it is desired to produce the desired decorative effects.

While in the form of the invention shown in the drawing it has been found preferable to utilize a relatively light liquid adhesive for securing the padding material to the backing sheet throughout the surface thereof. It is also possible to dispense with this adhesive and merely utilize the adhesive material 12 for securing the padding material to the backing sheet. After the padding material 11 has thus been secured in position upon the backing sheet 10 strips of crepe paper 13 or other suitably similar material are pressed upon the surface of the padded backing sheet throughout the area to which the relatively heavy coating of adhesive 12 has been applied. The padded backing sheet is then placed upon the bed 15 of a press which press includes a ram 16 vertically movable with respect to the bed. A frame 17 is removably secured to the ram of the press by means of a plurality of bolts 18 which frame serves to retain in position a die generally designated as 19. This die includes a plurality of blades 20 which project downwardly to engage the surface of the paper 13 which has been placed over the adhesively secured areas of the padding material. As the ram of the press descends these blades 20 serve to deform the padding material to provide the desired orna-

mental effects. In the particular form of the invention illustrated in the drawing a pair of these blades are disposed in substantially parallel relation and they together serve to provide a pair of substantially parallel indentations in the padded material which form a bead or ridge 21 therebetween which bead extends completely around the trim panel and provides an attractive panelled effect. If desired, additional blades may be provided in the die 19 serving to provide a rectangular bead 22 interiorly of the bead 21 or other blades may be disposed in any desired manner to provide the desired ornamental effects.

The blades 20 serve to press the padding material down into the relatively thick coating of adhesive which adhesive serves to retain the padding material in the form into which it is pressed by means of the blades 20. The covering paper 13 serves to prevent the padding material from 15 adhering to the blades of the press and serves to aid in retaining the padding material in the form in which it is embossed by means of the press. The surface of the paper 13 may be sprayed with a light coating of adhesive prior to its application to the padding material in order to retain 20 it firmly in the desired position if necessary.

After the padded backing sheet has thus been embossed a section of fabric finish material 23 is stretched over the padded backing sheet and the 25 marginal edges 24 thereof may be bent around and adhesively secured to the rear side of the backing sheet 10. This fabric finish material preferably has the surface thereof sprayed with a light coating of adhesive prior to application 30 to the padded backing sheet in order that it will be adhesively secured to the padding material throughout the entire surface of the trim panel. After the marginal edges of the fabric finish material have been secured to the backing sheet the 35 trim panel is again placed in the press and the ram of the press serves to conform the fabric finish material to substantially the configuration of the padding material and at the same time serves to tension the fabric finish material over 40 the surface of the trim panel. The adhesive covered surface of the fabric finish material will thus be retained in position closely adjacent the padding material and the decorative effects which have been produced in the padding material will thus be brought out in the completed 45 trim panel as a whole.

From the foregoing it will be appreciated that the above described process provides an extremely simple and convenient method of manufacturing 50 inner trim panels and the above described method has been found extremely satisfactory for commercial production.

In the modified form of the invention illustrated in Fig. 5 a section of padding material 25 is uniformly adhesively secured to a backing sheet 55

26. The padding material is then impregnated with latex or similar adhesive material throughout the portions thereof which are to be embossed. A section of fabric finish material 27 is sprayed with a light coating of adhesive stretched 60 over the surface of the padded backing sheet and has its marginal edges 28 adhesively secured to the rear side of the backing sheet 26. The trim panel as a whole is then placed in a press similar to that shown in Figure 2 and described above 65 and the padding and fabric finish material are embossed at the same time in one operation. The latex with which the padding material has been impregnated serves to retain the padding material and fabric finish material in embossed 70 condition and thereby serves to permanently retain the decorative effects produced by this embossing.

In the form of the invention shown in Figure 6 a backing sheet 30 has certain areas thereof 75 coated with a relatively heavy coating of thick adhesive material 31 and has a layer of padding 32 adhesively secured thereto. The fabric finish material 33 is applied to the padded backing sheet in substantially the manner described above and 80 the trim panel as a whole embossed by means of a die such as is shown in Figure 2 thus simultaneously deforming the fabric finish material and padding material throughout the predetermined desired areas in order to obtain the desired 85 embossed decorative effects. The padding material and fabric finish material will be retained in embossed condition by means of the relatively heavy layer of adhesive material 31 and the trim panel thus produced has been found to be 90 extremely satisfactory. It will be readily understood that the method described above and disclosed in Figure 6 of the drawing is substantially similar to the preferred embodiment of the invention except that only one embossing operation is necessary.

Many other and further modifications of the invention described above falling within the scope of the subjoined claim will become clearly apparent to those skilled in the art.

What is claimed is:

The method of forming inner trim panels which includes applying a relatively thick layer of adhesive material to predetermined portions of a backing sheet, securing a section of loosely felted padding material to said backing sheet applying protective strips of paper to the surface of said padding material in the areas thereof adjacent the areas to which said adhesive has been applied to said backing sheet and embossing said padding material before said adhesive has set whereby said adhesive will retain the padding in embossed condition.

ANDREW J. JAROSIK.
